UNITED STATES PATENT OFFICE

JACOB E. MARKLE, OF NASHVILLE, TENNESSEE

DESIGN FOR A GAME BOARD

Application filed June 17, 1932. Serial No. 44,107. Term of patent 14 years.

To all whom it may concern:

Be it known that I, JACOB E. MARKLE, a citizen of the United States, residing at Nashville, in the county of Davidson and State of Tennessee, have invented a new, original, and ornamental Design for Game Board, of which the following is a specification, reference being had to the accompanying drawing, forming part thereof.

In said drawing, Fig. 1 is a plan view of a game board, showing my new design, Fig. 2 is an enlarged view of part of the central portion, Fig. 3 is a sectional view.

The salient features of the invention include two concentric rows of representations

of dice faces with the dice faces in one row in radial alignment with the dice faces of the other row so as to form pairs which have alternately black backgrounds with white dots and white backgrounds with black dots. Also, one face of each pair is represented as square to the radial line and the other as diagonal thereto, the diagonally arranged representations being alternately in the inner and outer rows to present a staggered appearance.

I claim:

The ornamental design for a game board, as shown and described.

JACOB E. MARKLE.
